FROST PREVENTION MEANS

Thomas Gugliotta, Norwood, Mass.

Application July 19, 1951, Serial No. 237,603

1 Claim. (Cl. 20—40.5)

1 The present invention relates to a window frame and more particularly to a window frame of the type commonly employed on self propelled vehicles.

The primary object of the present invention is to inhibit the deposit of frost on a window pane and to melt any frost that may gather thereon.

Another object of the present invention is to employ the heat generated by the engine of a self propelled vehicle and to circulate heated air to uniformly heat the entire area of the window.

The above and other objects may be attained by employing this invention which embodies among its features a panel of transparent material having spaced passages extending therethrough between opposite side faces thereof, a tubular frame extending around the perimeter of the panel, and means opening into the panel to circulate heated air and or heated fluid therethrough.

Other features include clips carried by opposite edges of the panel and springs carried by the clips and engaging the frame to yieldingly suspend the panel in the frame.

Still other features include a nipple connected to the frame for connection to a duct leading to a similar frame and panel for conducting heated air or fluid to the second frame.

In the drawings:

Figure 1 is a front view in elevation of a window pane embodying the features of this invention.

Figure 2 is an enlarged partial fragmentary sectional view through the window pane illustrated in Figure 1.

Figure 3 is a sectional view taken on line 3—3 of Figure 2.

Figure 4 is a sectional view taken on line 4—4 of Figure 2.

Figure 5 is an enlarged view of one of the clips and resilient means, and

Figure 6 is a schematic view showing the device connected to a heat generator mounted on the exhaust manifold of a conventional vehicle engine and also illustrating a second window frame connected in the system.

Referring to the drawing in detail a window pane embodying the features of this invention designated generally 10 includes a panel 12 of transparent material, such as glass, having extending therethrough passages 14 which lie between opposite sides of the panel 12.

Encompassing the perimeter of the panel 12 is a tubular frame 16 which is preferably formed of light copper tubing which may be of circular configuration as shown in Figure 3, or of sub-

2

stantially elliptical configuration as shown in cross section Figure 4, the sides 16' of the frame 16 being recessed in the side edges of the panel 12.

If desired passages 14' may be provided in the panel 12 and adapted to communicate with similar openings 13 in the sides 16' as shown in Figure 4.

Opening into the bottom frame 16 adjacent one side thereof is a tubular duct 18 carrying a manually actuated valve 20 by means of which the passage through the duct 18 may be closed. A discharge nipple 17 is carried by the top of the frame 16 and is curved inwardly to direct into the vehicle heated air which has passed through the frame.

Lying adjacent the bottom of the tubular frame 16 is a conduit 22 carrying at one end a nipple 24 to which is connected a drain valve 26. This nipple is connected by means of a tube 28 to a suitable discharge pipe (not shown). The conduit 22 has a lateral opening 30 which mates with a similar lateral opening in the bottom of the tubular frame 16 so as to establish communication between the interior of said tubular frame and the interior of the conduit. A heat gage 32 is coupled to the conduit 22 adjacent the end thereof remote from the nipple 24 and opening into the top of the tubular frame 16 is a nipple which may be used as a discharge pipe to direct heated air into the interior of a vehicle or may be connected to another window in the body of the vehicle of similar construction.

Mounted on the exhaust manifold of the engine of the vehicle in which this improved window is used is a hood 34 having an open front end, and connected to the rear end of the hood is a flexible duct 36 which leads to and is connected with the valve 20. A motor driven fan 38 may be mounted in the hood 34 to force air through said hood 34 and into the frame 16.

In order to yieldingly support the transparent panel 12 in the tubular frame 16 I mount on the edge of the panel 12 at spaced points clips 40 carrying compression coiled springs 42 which bear on the frame as will be readily understood from viewing Figure 2, and the enlarged view Figure 5.

In use, with the valve 20 open and the engine of the vehicle running, the exhaust gases passing through the exhaust manifold will heat the latter and hence air entering the front open end of the hood 34 will be heated and conveyed to the interior of the tubular frame 16 to be discharged therefrom through the discharge nipple 17. Obviously the discharge nipple 17 may be coupled as by a flexible duct 44 to a similarly constructed

window in the vehicle. Should a faster circulation of air through the frame 16 be desired the fan 38 is set in motion. As the heated air passes through the tubular frame 16, the metal thereof becomes heated and radiates into the surrounding atmosphere which is conducted through the passages 14 to warm the transparent panel 12 and thus prevent the collection of frost thereon.

I wish to have it understood that minor changes in detail and construction of the various parts may be made without departing from the spirit of the invention, the scope of which is set forth in the appended claim.

What is claimed is:

A condensation prevention means comprising a panel of transparent material having a plurality of parallel spaced passages extending therethrough, a tubular vapor conducting frame encompassing the perimeter of the panel, said parallel passages communicating with said tubular

frame, a discharge nipple carried by and communicating with the top of said tubular frame, and means connected to the bottom of said frame for introducing heated air into said frame.

THOMAS GUGLIOTTA.
